Patented Feb. 3, 1959

184,350

PUFFED TEXTILE FABRIC

Henry E. Goforth, Winnsboro, S. C., assignor to United States Rubber Company, New York, N. Y., a corporation of New Jersey

Application April 16, 1958, Serial No. 50,494

Term of patent 14 years

(Cl. D92—1)

Fig. 1 is a plan view of a puffed textile fabric showing my new design;

Fig. 2 is a schematic sectional view of the fabric of Fig. 1 along the line 2—2;

Fig. 3 is a schematic sectional view of the fabric of Fig. 1 along the line 3—3, and

Fig. 4 is a schematic sectional view of the fabric of Fig. 1 along the line 4—4.

I claim:

The ornamental design for a puffed textile fabric, as shown.
